Marvin D. Monaghan, Garland, Tex.

Application June 4, 1956, Serial No. 41,759

Term of patent 14 years

(Cl. D80—11)

F/FIG. 1

F/FIG. 3

Fig. 1 is a top plan view of an optical frame display case, showing my new design;

Fig. 2 is a front elevational view thereof; and

Fig. 3 is a side elevational view of Fig. 1 partly in cross section, the square supporting blocks being omitted for convenience of illustration.

The optical frames shown in broken lines are for purposes of illustration only.

I claim:

The ornamental design of an optical frame display case, as shown and described.
